UNITED STATES PATENT OFFICE.

EUGENE LOWINGER, OF NEW YORK, N. Y.

ILLUMINATED SIGN.

Application filed August 23, 1927. Serial No. 214,856.

This invention is for subject matter similar to that disclosed in my application filed October 15, 1924, Serial No. 743,652.

The invention relates generally to illuminated signs, being intended more particularly for embodiment in signs such as are used on theatres, moving picture houses, or the like, to announce the program or its main features.

10 It has been found, with signs now in use, that those which are well adapted for daylight use do not have the maximum attention attracting properties when illuminated at night, while those designed more particularly for night illumination tend to have a flat and lifeless appearance when viewed in daylight.

20 The present invention has for an object to provide an improved sign of this type on which the above noted objections are obviated, the sign constructed according to my invention being well adapted for both day and night display.

25 For further comprehension of the invention and of the objects and advantages thereof, reference will be had to the following description and accompanying drawing, and to the appended claims in which the various novel features of the invention are 30 more particularly set forth.

Referring to the accompanying drawing forming a material part of this disclosure:

Fig. 1 is a face view showing one of the units of my improved sign, which has the 35 invention embodied therein.

Fig. 2 is a transverse vertical sectional view, taken on the line 2—2 of Fig. 1.

Fig. 3 is a transverse vertical sectional view, taken on the line 3—3 of Fig. 1.

40 Fig. 4 is a horizontal sectional view, taken on the line 4—4 of Fig. 1.

Fig. 5 is a fragmentary sectional view similar to Fig. 4 but showing a modification of the invention.

45 Figs. 6 to 10 are similar views, each showing a different modification.

The sign unit here shown is in the form of one of the letters of the alphabet, the common practice in sign work of this kind being to mount these units removably in the face of a hollow frame element, not shown on the drawing. The unit comprises a rectangular plate 10 which is suitably apertured as at 11 to form the letter, as herein shown by the letter H. A glass pane 12 is suitably fitted in the unit to extend across

the said letter aperture. As so far described, this is a well known construction, the present invention having more particular reference to the formation of the plate to provide a marginal portion for the various bars of the letter, this marginal portion being designed both to be in some degree illuminated by the light from the usual lamps shining through the glass pane, while at the same time a distinctive and contrasting border for the letter when the sign is viewed in daylight.

In the form of the invention shown in Figs. 1 to 4, the plate presents a forwardly projected flange 15 that extends completely around the letter aperture therein, this flange curving inward over the letter aperture as at 16 and terminating in a backwardly projecting element 17 that is oblique with respect to the glass pane, the rear edge of this element being spaced at a distance in front of the general plane of the plate 10. This glass pane is cut to the outline of the letter aperture and is seated between the walls of the flange, being located forwardly of the plate in contrast with the rear edges of the backwardly projecting element 17.

In the form of the invention disclosed in Fig. 5 the projecting flange 15 is formed with sharp edges 15', the members 17' are parallel to the main plate 10 and the glass 12 rests against the members 17'.

In the form of the invention shown in Fig. 6 the formation of the plate 10 is the same as that disclosed in Figs. 1 to 4, but the glass pane 12' is located in back of the plate body and extends from one edge of the plate to the other edge. In Fig. 7 the flange 15 is formed with sharp edges 15'.

The form of the invention shown in Fig. 8 differs only from that shown in Fig. 6 in that a wall element 20 is projected rearwardly from the element 17 to contact with the face of the pane 12', the opposed sides 100 of this wall element diverging rearwardly from one another. Light passing thru the pane 12' will brightly illuminate the inner faces of wall elements 20, and will illuminate the inner faces of the elements 17 to 105 a far lesser degree, when an onlooker is directly in front of the sign the wall elements 20 are hidden from view by the elements 17, and as the viewer moves to see the sign at certain angles, wall elements 20, and elements 17 are simultaneously visible. Thus 110 a contrast is produced which will add to the

prominence of the sign. In Fig. 9 the flange 15 is formed with sharp edges 15'. In Fig. 10, an angular flange 15^a is shown, with sharp corners 15' and parallel inner flanges 15^b.

While I have illustrated and described the preferred form, construction, and arrangement of the several elements employed, it will be understood that the device is nevertheless, susceptible of considerable modification therein, and I therefore reserve the right and privilege of resorting to all such changes as may be fairly embodied within the spirit and scope of the invention as claimed.

Having thus described my invention, what I claim as new and desire to secure by United States Letters Patent is:

1. A sign unit, comprising a frame plate, means for retaining a transparent pane on the rear side thereof, a character cut out of the frame, a flange projecting from the front of the frame plate and extended along the edge of the cut-out character, converging marginal elements extending from opposite sides of the front of the said flange to a

plane intermediate the front of the flange and the rear of the frame plate, and diverging wall elements extending from the ends of the converging marginal elements to the rear of the frame plate.

2. A sign unit comprising a frame plate, means for retaining a transparent pane on the rear side thereof, a character cut out of the frame, a flange projecting from the front of the frame plate and extended along the edge of the cut-out character, converging marginal elements extending from opposite sides of the front of the said flange to a plane intermediate the front of the flange and the rear of the frame plate, and diverging wall elements extending from the ends of the converging marginal elements to the rear of the frame plate, the said diverging wall elements being integral with the converging marginal elements, and the converging marginal elements being integral with the said flange.

In testimony whereof I have affixed my signature.

EUGENE LOWINGER.
